UNITED STATES PATENT OFFICE.

WILLIAM WARNER BROWN, OF OAK LANE, PENNSYLVANIA, ASSIGNOR, BY MESNE ASSIGNMENTS, TO THE FIFTH AVENUE BANK OF NEW YORK, OF NEW YORK, N. Y., A CORPORATION OF NEW YORK.

DYEING MACHINE.

Application filed March 17, 1923. Serial No. 625,912.

This invention relates to dyeing machines and the like and with respect to its more specific features to machines of the type provided with a rotatable yarn carrier, or 5 spider, which dips the material to be dyed into a vat of the dye liquor.

One of the objects of the invention is to provide a machine of the character referred to in which the rotatable yarn carrier is 10 also translatable into and out of the vat and in connection therewith to automatically position the yarn stick trip in stick actuating position for different translatory positions of the carrier.

Another object is to provide a strong and 15 efficient yarn stick trip and support therefor in conjunction with a rotatable and translatable yarn carrier.

Another object of the invention is the 20 provision of a practical yarn stick trip adapted efficiently to cooperate with yarn sticks supported at one end only of the sticks, one end of the stick being free for the application and removal of the skeins of 25 yarn.

Another object of the invention is to provide a practical machine of the character referred to which readily adapts itself to dyeing operations of different characters.

Another object of the invention is to provide a practical and improved mechanism 30 for tightening and loosening the yarn skeins to facilitate their application to and operation by the yarn sticks.

Another object of the invention is to provide a dyeing machine adapted for dyeing operations of different characters and which is simple in construction, readily operated and not apt to get out of order.

Other objects of the invention will in part 40 be obvious and will in part appear herein-after.

The invention accordingly comprises the features of construction, combinations of 45 elements, and arrangement of parts, which will be exemplified in the constructions hereinafter set forth and the scope of the application of which will be indicated in the claims.

For a fuller understanding of the nature 50 and objects of the invention reference should be had to the following detailed description taken in connection with the accompanying drawings, in which:

Figure 1 is a front elevation of a machine 55 embodying the invention;

Fig. 2 is a side elevation of the machine shown in Fig. 1;

Fig. 3 is a vertical sectional view showing the interior mechanism; 60

Fig. 4 is a central vertical sectional view taken at right angles to that in Fig. 3 and showing the arrangement of members adapted to hold the material to be operated upon and the construction by which these 65 members are supported;

Fig. 5 is a side elevation of the yarn stick tripping mechanism and its support;

Fig. 6 is a plan view of the tripping mechanism shown in Fig. 5; 70

Fig. 7 shows a further detail of the mechanism shown in Fig. 5;

Fig. 8 is a fragmentary enlarged section through the spider and the movable supporting ring showing a detail of the supports for certain of the yarn sticks, and 75

Fig. 9 is a fragmentary enlarged section through the movable yarn stick supporting ring intermediate arms of the supporting spider showing the construction for supporting a yarn stick at this point. 80

Referring more specifically to the drawing the machine comprises a casing having supporting posts 2, and a dome-shaped top 3 supported by the frame of the casing, the sides of the casing being provided with hinged doors 4, and a sliding door 6. The bottom of the casing is formed by a vat 1 of semi-cylindrical cross-section which is 85 suitably attached to posts 2. The vat 1 receives the carrier which supports the yarn for movement, the carrier in the present embodiment including a horizontally journaled rotatable spider 7 which as it rotates is adapted to dip the yarn into the vat. 90

The hinged doors 4 are each provided with a counter-balancing weight 5 for keeping the doors open or closed. For a similar pur- 95

pose the sliding door 6 is counter-balanced by a weight 8 attached to the door by means of a cord 9 passing over suitable pulleys at the top of the casing.

- 5 The material adapted to be dyed by the machine is preferably in the form of skeins, as yarn skeins, which may be looped over pairs of the two series of yarn sticks 10 and 11 which are rotatably supported by rings 10 12 and 13, respectively, held in position by quadrantal disposed arms 14 of the spider 7. As the spider is rotated about its shaft 15, the yarn skeins supported on the yarn sticks 10 and 11 will thereby be carried below the surface of the liquid in the vat 1 and thereafter raised out of the dye liquor in the vat 1 or the action may be repeated. In order to hold the yarn stretched firmly on the sticks 10 and 11, the rings 12 and 13 are constructed to be rotatable with respect to each other and for this purpose ring 12 is fastened to the arms 14 whereas ring 13 is rotatively supported by the arms 14. Ring 13 is provided with a rack 16 mounted thereon, this rack meshing with a gear 17 mounted on a shaft 18 which extends to a position adjacent one side of the casing. Shaft 18 is adapted to be rotated by means of a suitable worm gear 19 which in turn may be rotated by a crank 20 provided with a handle 21. Thus by rotating crank 20 the ring 13 may be rotated with respect to ring 12 thereby stretching taut the yarn skeins supported by and between respective pairs of the sticks 10 and 30 11 on the rings.

35 The spider 7 is composed of four arms 14 which are centrally disposed on the shaft 15 and support rings 12 and 13. The yarn sticks 10 extend from either side of the outer ring 12 being supported at one end only, the outer ends of these sticks being free. Similarly the yarn sticks 11 are supported at one end only in the inner ring 13. In order that the inner ring 13 may be rotated to the outer ring 12, certain of the yarn sticks are adapted to pass by arms 14 of the spider 7. To provide for this passage the inner ring 13 is constructed as shown in Fig. 8 wherein at the portion adjacent arms 14 the ring 13 is divided into two sections 22, each bearing laterally against the spider arm 14 at 23 and radially thereagainst at the surface designated 24. Intermediate adjacent arms of the supporting spider the opposite sections 50 55 of the movable ring 13 may be supported in spaced position by means of a spacer ring 14^a through which the spindle 36' of the yarn stick passes, as shown in Fig. 9.

60 Rotation of the spider or yarn carrier is effected by means of a suitable electric motor 25 which operates through a pinion 26, and idler pinion 27, and a gear 28 to rotate a worm 29 meshing with a worm gear 30 mounted on a shaft 31. Shaft 31 is also provided with a spur gear, or driving gear 32,

which meshes with the teeth of a ring gear 33 mounted on the outer ring 12 of the spider. Thus by the power of the motor 25 transmitted through the reduction gearing above described the spider, or carrier, may be 70 rotated, preferably at low speed, while in the vat to effect the passage of the yarn through the dye liquor. The proper spaced relation between the shafts 31 and 15 is assured by a bar or link 34 pivotally connected to each 75 of these shafts.

80 Adjacent their inner ends the yarn sticks on the outer ring 12 of the carrier have star wheels 35 fixed to rotate with the sticks. In the present embodiment, and as shown in Fig. 4, the yarn sticks 10 are in the nature of spools fast on a supporting shaft 36, rotatably mounted in bearings 37 and 38 of the outer ring 12, the star wheel 35 being fast to the shaft 36 and being disposed between the 85 bearings 37 and 38. The sticks 11 are carried on shaft 36' on the ring 13.

90 In order to facilitate the placing of the yarn skeins on the yarn sticks 10 and 11, and also their removal therefrom, and in order to subject the yarn to predetermined treatments, out of the dye liquor in the vat 1, the 95 yarn carrier, or spider, may be bodily moved, or translated, out of the dye liquor in the vat and the yarn sticks made to rotate under such conditions. The mechanism for translating the carrier into and out of the dye liquor in the vat 1 comprises a pair of link members 40 and 41 loosely engaging at one 100 end with portions of the shaft 15 of the carrier which shaft extends through the sides of the casing, the link members at their other ends being respectively connected with crank pins 42 and 43. Crank pin 43 is mounted on a crank 44, and crank pin 42 is mounted on a 105 worm wheel 45, the crank and the worm wheel being keyed or suitably fastened at either end of the shaft 46 mounted on top of the casing and in the same angular relation with respect to shaft 46. Worm wheel 45 is adapted to be rotated by a worm 47 and reduction gears 48, 49, 50 and 51 set in motion by an electric motor 52. As the power is applied to the worm wheel 45 to lift the 110 spider, or carrier, the shaft 15 is moved upwardly in guides 53 describing an arc of a circle about the shaft 31 as a center, since the link member 34 maintains a fixed distance 115 between the two shafts. It will therefore be seen that the rotary motion of the spider, or carrier, may be continued regardless of the translatory motion produced by rotation of the worm gear 45.

120 The tripping mechanism for rotating the 125 yarn sticks is illustrated in detail in Figs. 5, 6, and 7. The yarn stick tripping mechanism includes a trip comprising, in the present embodiment, a pair of pivotally supported fingers 55 and 56 between which is 130 rotatively supported a roller 57, there being

an arm 58 connected to said fingers. The numeral 59 indicates a trip tensioning spring, one end of which is connected to the arm 58 and the other end to a lug 60 fast 5 on a member of a trip positioning device.

The tripping mechanism is supported by a trip positioning device which, in the specific embodiment herein disclosed, is connected to maintain the trip in star wheel 10 actuating position for different positions of translation of the yarn carrier, or spider. The trip positioning device may include a trip supporting radius bar 61 pivoted coaxially with the stationary axis of the driving gear 32, this radius bar, in the present embodiment, being pivotally connected to the driving shaft 31. The radius bar 61 is a strong rigid member preferably curving as illustrated in Fig. 5 and provided with 15 the lug 60 intermediate its ends. For supporting the radius bar 61 in predetermined position there is provided a trip positioning yoke journaled or pivotally connected on the shaft 15 of the carrier. In the present 20 embodiment this supporting yoke includes a transverse rod 62 passing through the forked arms 63 and 64 of the radius bar 61, and two arms 65 and 66 disposed one on either side of the radius bar 61 and pivotally 25 connected to the axis or shaft 15 of the carrier, the upper ends of the arms 66 receiving and supporting the transverse rod 62. The supporting arms 65 and 66 are spaced apart 30 sufficiently to permit the yarn sticks to clear 35 the same as the carrier rotates.

It will be observed that the radius bar 61, the supporting arms 66, and the link 34 are related to each other as are the sides of a triangle, this relation being more apparent 40 when the projection of these three elements on a plane surface is considered. Thus the radius bar 61 in conjunction with the supporting yoke and the link 34 provide, in effect, an articulated rigid frame journaled 45 on the driving shaft 31. Likewise this frame, being pivotally connected to the shaft 15, moves synchronously in response to the translatory movement of the carrier or spider effected by the worm 47 and its operative 50 connections to the shaft 15. The driving shaft 31 is supported in suitable stationary bearings in the casing and is operatively connected through the gears 32 and 33 to effect rotation of the carrier, or spider. 55 And this operative connection between the gear 32 and the gear 33 is maintained though the trip positioning device be rotated on the shaft 31.

As the carrier of the spider rotates, the star wheels 35 engage the trip roller 57 and the shock of the contact therebetween is absorbed in the spring 59. Should the star wheels for any reason fail to rotate, the roller 57 will be forced aside, the spring 59 being adapted to yield under such circum-

stances to permit the star wheel to pass by. Upon release of the roller 57 the arm 58 is prevented from being injured by the recoil due to the tension of the spring 59, by means of a spring bumper device which comprises 70 a U-shaped guide 70 bolted to a stud 71 on the radius arm 61 and upon each arm of which there is provided a spring 72 pressing against a cross piece 73 lying in the path of the arm 58 and acting as a bumper therefor. The counteracting tension in the springs 72 and the spring 59 is sufficient to maintain the roller 57 in proper position to engage the star wheels 35 as they pass by. 75

In operation the motor 25 may be energized to effect rotation of the yarn carrier and when said carrier is in the vat the yarn will be transported through the dye or other liquor in the vat. The trip positioning device will support the tripping mechanism in 80 the path of the star wheels of the yarn sticks and each star wheel will be rotated so that part of the yarn in contact with the sticks will be moved into position free of contact with the sticks so as to readily absorb the dye liquor. Simultaneously with the rotation of the carrier, or between alternate rotations thereof, the motor 52 may be energized thereby causing the carrier to be 85 translated and lifted from the dye liquor. The carrier may be held suspended above the dye liquor by arresting operation of the motor 52 or the motor 52 may be permitted to continue to operate so as to alternately 90 translate the carrier into and out of the dye liquor. Whatever be the position of the 95 yarn carrier with respect to the vat, it will be seen that the trip positioning device will be actuated to maintain the tripping mechanism in stick rotating relation to the star wheels. Furthermore it will be noted that the spring 59 which tensions the trip is wholly supported by the trip positioning device and in such manner that its tension 100 is not affected by the movement of the trip positioning device.

By reason of the yarn sticks being rotatively connected to the carrier at one end only, the outer ends of the sticks being free, 115 these sticks may be mounted on the carrier in a permanent manner, the skeins of yarn being readily applied over the free outer ends of these sticks. By operating the crank 120 the inner series of yarn sticks on the ring 13 may be rotated relative to the outer series of sticks on the ring 12 thus providing for 120 adjusting the distance between the respective pairs of sticks supporting the skeins and facilitating the application and removal of the skeins.

Thus by the above construction are accomplished among others the object hereinbefore referred to.

Since certain changes may be made in the 130 above construction and different embodi-

ments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. In a dyeing or like machine, in combination, a vat for the treating liquor, a rotatable carrier translatable into and out of the liquor in the vat and having rotatable yarn sticks with star wheels connected thereto, a yarn stick trip positioned for cooperation with said star wheels, a supporting arm for said trip mounted at the axis of said rotatable carrier and disposed radially with reference thereto, a supporting bar for said arm articulated thereto and having a supporting connection laterally disposed from said supporting arm whereby said arm and bar are movable with movement of said carrier into or out of said vat so as to maintain said trip in star wheel actuating position for different positions in the translatory movement of said carrier.
2. In a dyeing machine or the like, in combination, a vat, a rotatable carrier translatable into and out of the liquor in the vat having rotatable yarn sticks with star wheels, a yarn stick trip, a trip positioning device and a rotatable member having a stationary axis operatively connected to rotate said carrier, said trip positioning device including a trip supporting radius bar pivoted coaxially with said stationary axis.
3. In a dyeing machine or the like, in combination, a vat, a rotatable carrier translatable into and out of the liquor in the vat having rotatable yarn sticks with star wheels, a yarn stick trip, a trip positioning device, a rotatable member having a stationary axis operatively connected to rotate said carrier, said trip positioning device including a trip supporting radius bar pivoted coaxially with said stationary axis, and a radius bar support connected to the axis of said carrier.
4. In a dyeing machine or the like, in combination, a vat a rotatable carrier translatable into and out of the liquor in the vat having rotatable yarn sticks with star wheels, a yarn stick trip, a trip positioning device, a rotatable member having a stationary axis and being operatively connected to rotate said carrier, said trip positioning device including a trip supporting radius bar pivoted coaxially with said stationary axis, and a radius bar support connected to

the axis of said carrier, said radius bar support including a transverse rod connected to said radius bar and to which said trip is pivoted, and rod supporting arms respectively at each side of said radius bar connected to the axis of said carrier.

5. In a dyeing machine or the like, in combination, a vat, a rotatable carrier translatable into and out of the liquor in the vat having rotatable yarn sticks with star wheels, a yarn stick trip, a trip positioning device, a rotatable member having a stationary axis operatively connected to rotate said carrier, said trip positioning device including a trip supporting radius bar pivoted coaxially with said stationary axis, and a trip tensioning spring one end of which is connected to the trip and the other end to said trip positioning device.

6. In a dyeing machine or the like, in combination, a vat, a rotatable carrier translatable into and out of the liquor in the vat, said carrier having gear teeth and rotatable yarn sticks with star wheels, a driving gear meshing with the teeth of the carrier gear, a yarn stick trip, and a trip positioning device including a radius bar pivoted coaxially with said driving gear, a transverse rod to which said radius bar is connected, and rod supporting arms connected to the axis of said carrier at either side of the carrier.

7. In a dyeing machine or the like, in combination, a vat, a rotatable carrier having rotatable yarn sticks, means adapted to cooperate with the shaft of said carrier to raise and lower the carrier relative to the vat, a yarn stick trip, a driving shaft, a carrier driving gear on said driving shaft, and a rigid trip positioning frame connected to the shaft of said carrier and pivoted coaxially with said driving shaft.

8. In a dyeing machine or the like, in combination, a vat, a rotatable carrier having rotatable yarn sticks, means adapted to cooperate with the shaft of said carrier to raise and lower the carrier relative to the vat, a yarn stick trip, a driving shaft, a carrier driving gear on said driving shaft, a rigid trip positioning frame connected to the shaft of said carrier and pivoted coaxially with said driving shaft, said frame including a radius bar journaled on said driving shaft, and a yoke mounted on said carrier shaft and connected to said radius bar.

9. In a dyeing machine or the like, in combination, a vat, a rotatable carrier having rotatable yarn sticks, means adapted to cooperate with the shaft of said carrier to raise and lower the carrier relative to the vat, a yarn stick trip, a driving shaft, a carrier driving gear on said driving shaft, a rigid trip positioning frame pivotally connected to the shaft of said carrier and pivoted coaxially with said driving shaft,

said frame including a radius bar journaled on said driving shaft, a yoke journaled on said carrier shaft and connected to said radius bar, and a link pivotally connected 5 to said carrier shaft and said driving shaft, the projection of said radius bar, yoke and link on a plane surface forming a triangle.

10. In a dyeing machine or the like, in combination, a vat, a rotatable and translatable carrier, yarn sticks rotatably connected to the carrier and having free outer ends, star wheels adjacent the inner ends of said sticks, a yarn stick trip in alignment with the rotary path of said star wheels, a driving gear for rotating said carrier, and a trip positioning device comprising an articulated rigid frame pivoted coaxially with said driving gear and movable on its pivot in response to translation of said carrier.

20. 11. A dyeing and scouring machine comprising, in combination, a rotatable spider, yarn sticks supported by said spider and a trip mechanism adapted to rotate said yarn sticks, said trip mechanism including a pair 25 of pivotally supported fingers, and a roller supported between said fingers.

12. A dyeing and scouring machine comprising, in combination, a rotatable spider, yarn sticks supported by said spider and a trip mechanism adapted to rotate said yarn sticks, said trip mechanism including a pair 30 of pivotally supported fingers, a roller supported between said fingers, an arm extending rearwardly of said fingers and a spring 35 tensioning said arm.

13. A dyeing and scouring machine including, in combination, a rotatable spider, yarn sticks supported by said spider and a trip mechanism adapted to rotate said yarn 40 sticks, said trip mechanism including a pair of pivotally supported fingers, a roller supported between said fingers, an arm extending rearwardly of said fingers, a spring tensioning said arm and a spring pressed 45 bumper against which said arm is pressed by said spring.

14. A dyeing and scouring machine comprising, in combination, a rotatable spider, an outer ring and an inner ring supported 50 by said spider, yarn sticks on said rings, each of said yarn sticks being pivotally supported at one of its ends on one of said rings, means to rotate one of said rings with respect to the other ring, a power driven 55 shaft, means associating said shaft with said spider and adapted to cause rotation thereof,

and means to rotate said spider orbitally with respect to said shaft.

15. In a dyeing machine or the like, a dye vat, a reel rotatable in said vat, a driving 60 shaft having connections with said reel for rotating the same, yarn sticks rotatably mounted upon said reel, a yarn stick trip cooperating with said yarn stick to move the latter as said reel rotates, lifting mechanism 65 for raising and lowering said reel, and a link connection between said reel and said driving shaft to maintain the former in driving relation with the latter when the reel is either in raised or in lowered position.

16. In a dyeing machine or the like, a dye vat, a reel rotatable in said vat, a driving shaft having connections with said reel for rotating the same, yarn sticks rotatably 70 mounted upon said reel, a yarn stick trip cooperating with said yarn stick to move the latter as said reel rotates, lifting mechanism 75 for raising and lowering said reel, a link connection between said reel and said driving shaft to maintain the former in driving relation with the latter when the reel is either in raised or in lowered position, and a link connection between said reel and said 80 yarn stick trip to maintain the latter in operative position when the reel is in raised or in lowered position.

17. A dyeing and scouring machine comprising, in combination, a rotatable spider, an outer ring and an inner ring supported 85 by said spider, yarn sticks on said rings, each yarn stick being rotatably supported on one of said rings, means to rotate one of said rings with respect to the other ring, a power driven shaft, power connections between said shaft and said spider for transmitting rotative movement to the latter, a star wheel mounted on each said yarn stick on one of said rings, a trip mechanism cooperative with said star wheels, link members to maintain the trip mechanism at a fixed distance from center of rotation of said 95 spider, and means to rotate said spider orbitally with respect to said shaft and including a rotary member, a link connecting the axis of said spider on an eccentric point on said member, and a radius rod extending between the spider axis and said power driven shaft.

In testimony whereof I affix my signature.

WILLIAM WARNER BROWN.
